UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed May 29, 1925. Serial No. 33,621.

This invention relates to machines for typing address-stencil-cards, and particularly to means for holding the stencil-cards in machines of the class wherein the card is presented to the printing point on the platen and is progressively raised step by step by means of a frame to line-space the same. Such a machine is disclosed in the patent to Elliott, No. 1,378,771, dated May 17, 1921. In such machines, the top of the card is clipped by jaws provided upon said frame. An object of this invention is to carry the card down to a lower point than is practicable where such jaws are employed. To this end the card is inserted in a framing or pocket, designed to deflect the card and to present it to the printing point in front of the platen.

The card-receiving frame comprises side-guides connected by a cross-piece which serves as a support or rest for the bottom edge of the card. The card is laterally located and squared against the bottom support and is held in place by means of front fingers extending upwardly from the bottom cross-piece.

Another feature of this invention relates to means whereby cards of different widths may be handled with the same card-holding device, and to this end there is provided a supporting member fast to arms which are rockably mounted at the rear of the platen and are raised to line-space the card. The supporting member is provided with upturned edges between which the wider cards are placed. In order to accommodate narrower cards in the same card-holder, there are provided filling blocks or spacers which are secured to the supporting member at the sides thereof.

Another feature relates to the manner of constructing the card-holder which enables it to be made of comparatively thin material and at the same time effectively deflect and hold the card. The supporting member comprises a frame designed to fit the side and bottom edges of the card and is bent at the bottom forming a pocket or rest for the bottom edge of the card. In order to closely hold the card against the platen, the card-holder is provided with a front frame which may be an upwardly extending portion of the rear frame. Because of the comparatively thin material of the card-holder there is provided a spring effective to press upon

the upper frame so that it will bear heavily upon the lower frame, and thus effectively grip and deflect the card.

Other features and advantages will hereinafter appear.

In the accompanying drawings, Figure 1 is a side view in elevation of the stencil device as applied to an Underwood standard typewriting machine.

Figure 2 is a front view in elevation of the card-holding frame and the platen of the machine.

Figure 3 is a perspective view of the card-holding frame, showing the filling-blocks both in their effective and ineffective positions.

Figure 4 is a cross-sectional view through the line 4—4 of Figure 2.

Figure 5 is a perspective view of the filling-blocks.

A stencil-card, consisting of a paper-frame 10 for keeping in a flat condition a stencil-sheet 11 mounted in said frame, is placed in a card-holding frame 12 to be presented to the printing point over a platen 13, to be struck by type-bars 14. It is sometimes desirable to write with the ribbon in printing position upon the frame of the card, and then to withdraw the ribbon and cut upon the stencil-sheet with the bare type. To this end the Underwood machine is provided with mechanism to quickly render operative or to silence the ribbon-vibrating mechanism. Said mechanism is fully disclosed in the patent to F. A. Cook, No. 926,050, dated June 22, 1909.

The card-holding frame is secured by means of screws 15 to the ends of the supporting-arms 16, and includes two downwardly extending side-guides 17 forming a backing and provided with ribs 18 to laterally position the card. The two side-guides are connected by a connecting-piece 19, which piece is bent outwardly and up forming two front card-holding fingers 20. The fingers are flared outwardly at 21 away from the side-guides at the top thereof to facilitate the insertion of the card between the guides and the fingers, the two members forming a pocket for the card which rests by its bottom edge upon the edge 22 of the connecting-piece 19. In order that the card-holding frame may be suitable for use on existing machines having a card-pocket 23 at the end of the supporting-arms 16, the

side-guides are provided with a forwardly-inclined tongue 24 at the top thereof adjacent the screws 15 to facilitate the removal of the card from the frame 12.

- 5 Owing to the limited space available in the Underwood machine between the platen and the ribbon-vibrating mechanism, it is desirable to construct the card-holding frame of very thin material, so that the card-holding frame may be bent radially with the shaft 25 supporting the arms 16 and tangent to the platen, as shown in Figure 1. The card-holding frame is reinforced by the ribs 18 which stiffen the frame and slightly deflect the card inwardly to clear some of the mechanism of the machine and to provide a clearer impression of the types by eliminating shadowing of the types in the case not being printed.
- 10 The fingers 20 are reinforced by means of springs 26 to increase the gripping action thereof. Said springs are secured to the arms 16 by means of the screws 15 and are provided with loops 27 behind the side-guides 17 and are bent over the fingers at 28. In this manner it is possible to use comparatively thin material for the card-holding frame and at the same time effectively grip the card.
- 15 Means are provided in this invention for the selective use of cards of different widths without replacing the card-holding frame. To this end, the card-holding frame is made wide enough to receive the wider cards between the ribs 18, and when it is desired to handle narrower cards, such as the card shown in Figure 2, then there are provided filling-blocks 29 which are placed behind the springs 26 bearing against the ribs 18 of the side-guides 17. The filling-blocks 29 are provided with lugs 30 engaging with slots 31 in the ribs 18 of the side-guides 17, said lugs being effective to hold the blocks near the ribs 18 and to prevent them from being vertically displaced relatively to the frame. Offsets 21^a, carried by the flared portions 21 of the fingers 20, press upon the filling-blocks 29 to prevent displacement thereof. The springs 26 also press lightly upon the filling-blocks 29 and aid the offsets 21^a in holding them in place.

20 The line-spacing mechanism comprises the arms 16 supported at the rear of the platen by the shaft 25 fast to the platen-frame 32. The free ends of the arms carry the card-holding frame fast thereto and are gradually raised by the action of a cam 33 rotatably mounted on a shaft 34 journaled in the arms 16. Said cam is supported by a fixed roller 35 also borne by the platen-frame through a cross-shaft 36. To line-space the card, that is to say, to raise the card-holding frame one space, a finger-wheel 37 is rotated one tooth of a ratchet 38, which is arrested by a tooth 65 of a pawl 39 mounted on one of the arms 16.

In order to facilitate the insertion of the wider cards in the card-holding frame, the ribs 18 are slightly flared out at 40. The blocks 29 are also provided with a cut-away portion at 41 to form a chute or conductor 70 for the cards, and are bent to conform with the radial outline of the side-guides 17.

Variations may be resorted to within the scope of the invention, and portions of the improvements may be used without others. 75

Having thus described my invention, I claim:

1. In a typewriting machine having a revoluble platen and typing instrumentalities, means for presenting a stencil-card to the printing field, said means including, in combination, a rockably-mounted frame and a card-holding member borne by said frame, said card-holding member including side guiding plates having upturned edges effective to laterally locate the card, a cross-connecting piece between the guiding plates at the bottom thereof, said cross-connecting piece serving as a rest for the bottom edge of the card, resilient finger-pieces effective to grip the card and to hold it against the guiding plates, and means effective to locate cards of a narrower width within the card-holding member, said last-mentioned means including spacing blocks having lugs engaging with slots in the upturned edges of the side guiding plates, and means for resiliently holding the blocks in place. 95

2. In a typewriting machine having a revoluble platen and typing instrumentalities, means for presenting a stencil-card to the printing field, said means including, in combination, a rockably-mounted frame and a card-holding member borne by said frame and fast to the free end thereof, said card-holding member including downwardly-extending curvate strips adjacent the platen and substantially radial with the supporting shaft of the rockably-mounted frame, said strips being provided with lateral guides for the card and being connected at the bottom thereof with a cross-piece having an upturned edge effective to support the card by its bottom edge, and means for holding the card against the curvate strips, said last-mentioned means including upwardly-extending fingers forming an integral part of the card-holding member, and resilient springs actuating upon the uppermost ends of the fingers to increase the gripping action thereof. 110

3. In a typewriting machine having a revoluble platen and typing instrumentalities, means for presenting a stencil-card to the printing field, said means including, in combination, a rockably-mounted frame and a card-holding member borne by said frame and fast to the free end thereof, said card-holding member including downwardly-extending curvate strips adjacent the platen 125

and substantially radial with the supporting shaft of the rockably-mounted frame, said strips being provided with lateral guides for the card and being connected at the bottom thereof with a cross-piece having an upturned edge effective to support the card by its bottom edge, and means for holding the card against the curvate strips, said last-mentioned means including upwardly-extending fingers forming an integral part of the card-holding member, and resilient springs actuating upon the uppermost ends of the fingers to increase the gripping action thereof, said springs having a double loop, one of the loops being anchored to the curvate strips at the rear thereof and the ends of the springs bearing upon the ends of the upwardly-extending fingers.

4. In a front-strike machine for typing on stencil-cards, the combination with a platen, of an overhead frame movable up and down relatively to the platen, a card-holding frame carried pendent by said movable frame at the front of the platen and including side and bottom gages for a card, resilient fingers adjacent each side of said card-holding frame for pressing the card against the body thereof, spacing blocks adjacent each of said fingers for gaging a narrower card, the free ends of the fingers being offset to engage the blocks, whereby to hold them to said card-holding frame, and springs engaging the free ends of said fingers to aid them in holding any of the cards to said card-holding frame, said springs also overlying the blocks and thereby assisting the fingers in holding said blocks in gaging position.

5. In a front-strike machine for typing on stencil-cards, the combination with a platen, of an overhead frame movable up and down relatively to the platen, a card-holding frame carried pendent by said movable frame at the front of the platen and including side and bottom gages for a card, resilient fingers adjacent both sides of the card-holding frame for holding said card thereto, removable spacers extending the full vertical length of the card adjacent both sides thereof, means for holding the spacers against vertical displacement, and springs overlying the spacers and pressing said fingers toward said card-holding frame, whereby to grip the card and at the same time aid in holding said spacers to said card-holding frame.

6. In a typewriting machine having a rev-

oluble platen and typing instrumentalities, means for removably holding a stencil-card in the printing field, including, in combination, a support and a card-holding frame mounted thereon having side-guiding plates with gaging edges effective to laterally locate the card, there being a cross-piece connecting said plates at their lower extremities to form a lower limit for said card, and retaining fingers to hold said card against said plates, and rigid means on said frame above said retaining fingers to deflect and strip said card from said frame when said card is fed upward from said cross-piece.

7. In a typewriting machine having a revoluble platen and typing instrumentalities, means for removably holding a stencil-card in the printing field, including, in combination, a support, a card-holding frame having side-guiding plates with gaging edges effective to laterally locate the card, there being a cross-piece connecting said plates at their lower extremities to form a lower limit for said card, and retaining fingers to hold the card against said plates, and a pair of integral tongues upon the upper extremity of each of said plates, one tongue on each plate-member being secured to the aforesaid support whereby to secure said frame, and the other tongue on each plate being inclined forwardly above said retaining fingers to form deflecting fingers for said card during the removal thereof from said frame.

8. In a typewriting machine having a revoluble platen and typing instrumentalities, means for removably holding a stencil-card in the printing field, including, in combination, a support, a card-holding frame having a pair of laterally spaced plates adjacent the platen provided with side-guiding edges effective to laterally locate the card, and which plates are connected at their lower extremities by a cross-piece and terminate at their upper extremities in a pair of tongues, the outer extreme tongue on each plate being secured to said support whereby to anchor said frame, and the inner tongue of each pair being inclined away from said support to deflect the card from the machine during its removal from said frame, and a retaining finger adjacent each of said plates terminating below said deflecting tongues and provided with auxiliary tension-means to increase the gripping effect of said tongues on said card.

ALFRED G. F. KUROWSKI.
